Specification for Design.

Patented Mar. 31, 1914.

Application filed February 21, 1913. Serial No. 750,009. Term of patent 7 years.

To all whom it may concern:

Be it known that I, WILLIAM A. FRENCH, a citizen of the United States, residing at Minneapolis, in the county of Hennepin and State of Minnesota, have invented a new, original, and ornamental Design for Humidors, of which the following is a specification, reference being had to the accompanying drawing, forming part thereof.

The figure is a perspective view of a humi-

dor with the cover down made in accordance with my novel design.

I claim:

The ornamental design for a humidor, as shown.

WILLIAM A. FRENCH.
